UNITED STATES PATENT OFFICE

2,451,211

CABINET, CHEST, AND SIMILAR ARTICLES

Lee Gersten, New York, N. Y.

Application April 24, 1947, Serial No. 743,587

7 Claims. (Cl. 229—23)

1

The present invention relates to cabinets, chests, wardrobes and containers generally of the knock-down type made of paperboard and the like with wood trim if desired, and particularly wherein the ends are fitted onto the body portion.

The principal object of this invention is to provide a novel and improved locking joint to anchor the end members onto the body portion of the container, whereby erection of the article is facilitated and substantial strength added to the resulting structure.

Another object hereof is to provide a novel and improved locking joint construction, which is, simple to make, easy to use, which permits quick assembly, reasonable in cost, and effective in carrying out the purposes for which it is designed.

Other objects and advantages will become apparent as this disclosure proceeds.

In the accompanying drawings forming part of this application, similar characters of reference indicate corresponding parts in all the views.

Fig. 1 is a perspective view of a chest embodying the teachings of this invention.

Fig. 2 is a perspective view of a cabinet made in accordance with this invention. It is to be noted that both said chest and this cabinet are of identical construction; the only differences being dimensional and their respective use positions.

Fig. 3 is a perspective view of one of the end members which fit telescopically onto the body of said containers.

Fig. 4 is a perspective view showing an embodiment of the body member.

Fig. 5 is a section taken at lines 5—5 in Fig. 1.

Fig. 6 is an enlarged fragmentary sectional view of the structure used to lock an end member to the body member.

In the drawings, the numeral 15 indicates generally the body of the chest illustrated in Fig. 1, which body when of suitable dimensions as 15', may serve for the cabinet shown in Fig. 2. Such body members, made for instance of fibre board or other cardboard-like material, may include a suitable door component 16, all made from a single blank, cut and folded as in Fig. 4, to form a rectangular tubular structure when the door is considered in closed position.

End members 17, adapted to be telescopically set onto the open ends of such tubular structure, each comprise a rectangular panel 18 of fibre board, which panel is secured in any suitable

manner in a frame of wood 19, extending from said panel as a flange from one surface and along its perimeter, whereby each end member can be mounted onto the body 15, as mentioned.

Heretofore, such ends were nailed or otherwise pinned to the body, to complete the assembly. Erection was cumbersome, even difficult, and assembled, the structure was weak and unsturdy. To overcome these difficulties, the present invention provides novel structure to look or anchor the ends 17 onto the body member 15.

Along the edge portion of one of the walls of the body member 15, which enters the end member 17, is fixed a slat 20, onto the exterior surface of such wall. The longitudinal edge of said slat 20, which is most remote from the said edge of the body member, is bevelled so that said bevelled edge and the body member's exterior surface, form an acute angle.

Extending outwardly from the interior of the end member 17, along and on that side of wood frame 19, which is to lie adjacent the slat-carrying wall of the body member 15, is a slat-carrying member 21 made of fibre board, which may be integral with the panel 18. When end 17 is set onto the body member 15, slat 20 rests on said member 21, very near panel 18, but said member 21 is of such dimension, that it extends beyond the bevelled edge 20' of slat 20. Along such portion of itself as extends beyond said edge 20', said member 21, carries secured thereon a slat 22, whose bevelled edge 22' is in contact with edge 20'. Said edge 22' of slat 22, is evidently the edge thereof nearest panel 18, and the angle between said edge 22' and member 21, is an acute angle, which preferably is equal to the angle between bevelled edge 20' and body member 15.

In manufacture, the end members 17, are fully made with member 21 and slat 22 secured thereon, as shown in Fig. 3, and the body member 15, is fully made with slats 20 secured thereon as shown in Fig. 4. The article is shipped "knock-down," to be assembled by the ultimate user. For convenience and better practice, the slats 21 on the body member 15, should be on the bottom wall, when the container is a chest as Fig. 1, and on the rear wall of the body 15' of the cabinet of Fig. 2. Space marked "A" should be made as small as is practical, relying more on the resilient or yielding nature of member 21, to permit the assembly whereby the slats 20 and 22 "hook" one another.

To assemble, the body member is bent or set up to form as in Fig. 4. The end members 17 are mounted so that the bevelled slats 20 and 22 in-

terlock as explained. The as yet free edges of the body member 15, are secured to the respective wood frames 19 of the end members 17, by means of nailing or suitable fasteners 23. Wood trim members 24 or 24', are mounted to lend appearance and enhance rigidity.

It is to be noted, that to get the end members 17, on or off the body member 15, said end members need receive a swinging movement, as if they were hinged at the hook joint.

Inclusion of a door member being optional, the remainder of the body member 15, may be deemed channel in form. Also, the entire container and its trimmings may be void of wood, and made wholly of paperboard. It is desirable for practical reasons, that slats be of wood.

This invention is capable of numerous forms and various applications without departing from the essential features herein disclosed. It is therefore intended and desired that the specific description herein be deemed illustrative and not restrictive and that the patent shall cover all patentable novelty herein disclosed; reference being had to the following claims rather than to the specific embodiment herein to indicate the scope of this invention.

The following are the claims:

1. In a container of the character described, a paperboard body member having walls forming a channel, a separate paperboard end member, a perimetric flange angularly disposed on said end member whereby said end member is adapted to be telescopically set onto the body member to cover an end thereof, a component carried by said end member and extending beyond said flange, a slat carried by said component, a second slat carried by the body member; said second slat being positioned between the first slat and the end member when said end member covers an end of the body member; each of said slats presenting a bevelled edge; said slats being adapted to be set with said bevelled edges in contact with each other whereby said end member is hooked to the body member while the end member is in position covering said end of the body member, and detachable therefrom by a motion including a swinging movement of said end member with respect to the body member, and distortion of the component.

2. An article as defined in claim 1, wherein the component extending from the end member is of material having resilient nature.

3. An article as defined in claim 1, wherein the component extending from the end member is an integral part of the flange.

4. An article as defined in claim 1, wherein the component mentioned is part of the flange and wherein the flange is integral of the end member.

5. In a container of the character described, a paperboard body member forming of a flat blank by bending along parallel lines to form a channel having flat walls, a separate paperboard end member, a perimetric flange angularly disposed on said end member whereby said end member is adapted to be telescopically set onto the body member to cover an end thereof, a component carried by said end member and extending beyond said flange, a slat carried by said component positioned thereon parallel to the plane of the end member, a second slat carried on a wall of the body member parallel with the end of said wall which receives the end member; said second slat being positioned between the first slat and the end member when said end member covers the body member; each of said slats presenting a bevelled edge; said slats being adapted to be set with said bevelled edges in contact with each other whereby said end member is hooked to the body member while the end member is in position covering said end of the body member, and detachable therefrom by a motion including a swinging movement of said end member with respect to the body member and distortion of the component; the plane of contact of said bevelled edges extended, intersecting the material of the end member.

6. An article as defined in claim 5, wherein the component extending from the end member is of material having resilient nature.

7. An article as defined in claim 5, wherein the flange is of wood.

LEE GERSTEN.
